CLAIM

The ornamental design for the combination flashlight and pepper spray device, as shown and described.

DESCRIPTION

FIG. 1 is a perspective view taken from the front of the device.

FIG. 2 is a view in side elevation from the front of the device.

FIG. 3 is a view in side elevation from the rear of the device.

FIG. 4 is a view in side elevation taken from the left side of the device.

FIG. 5 is a view in side elevation taken from the right side of the device.

FIG. 6 is an end view taken from one end of the device;

FIG. 7 is an end view taken from the opposite end of the device; and,

FIG. 8 is an enlarged view of the device taken from the area labeled 8 in FIG. 2.

The broken lines in the drawings depict portions of the combination flashlight and pepper spray device that form no part of the claimed design. The additional rectangular dashed lines shown in FIGS. 2 and 8 are for annotative purposes only and form no part of the claimed design.

1 Claim, 5 Drawing Sheets
